UNITED STATES PATENT OFFICE

PASQUALE FRIGIOLA, OF NEW YORK, N. Y.

WEATHER STRIP FOR WINDOWS

Application filed April 3, 1929. Serial No. 352,293.

My invention relates to weatherstrip devices for the sliding sashes of windows and the like, and particularly to weatherstrips of folded sheet metal, in which the fold of the sash member slides on and interlocks with the fold of the parting strip or window stop member.

The object of my invention is to simplify, cheapen, and improve the construction, arrangement, and attachment of metal strips of this class, and to provide for the removal of either sash from the window frame without detaching the weather stripping.

To this and other ends, my invention in its present preferred embodiment comprises in its entirety, a fixed folded interlocking strip or stop member having fastening plates secured to both the face and side of the parting strip or stop, and a sliding folded sash member having its fold sliding on the outside of the fixed member and having a fastening plate secured to the outside of the sash.

My invention also comprises a recessed molding to cover the outside sliding sash member and inside fixed member.

My invention also comprises interlocking strip members made in separable upper and lower sections so that the lower section can be removed to permit the removal of the sashes without detaching the weather strips.

In order that my invention may be fully understood, I shall first describe in detail the mode in which I at present prefer to carry this invention into practice.

Reference is to be had to the accompanying drawings forming part of this application for patent, in which like parts are designated by the same numbers in all the figures.

Figure 1 is a sectional plan view of a window with vertically sliding sections weatherstripped according to my invention.

Figures 2 and 3 show alternative forms of the weather strip members.

Figure 4 is a sectional elevation on the line 4-4, Figure 1.

In the drawings, 5 designates the window frame, 6 the sliding upper sash, 7 the sliding lower sash, 8 the outside window stop, and 9 the parting strip.

I prefer to make my metal weather strip

as shown in Figures 1, 2, and 4, of a sash member 10 and parting companion and interlocking strip or stop member 11.

The sash member 10 is formed of sheet metal bent to form a straight longitudinal fastening plate 12 and a fold 13 offset at 14 from the fastening plate and having its side members 15 and 16 parallel in cross-section to the fastening plate.

The companion strip or stop member 11 is formed of sheet metal with a longitudinal fastening plate 17; a fold 18 whose member 19 is a continuation in cross-section of the fastening plate 17, the fold 18 being adapted to fit closely and slide lengthwise in the fold 13 of the sash member 10, and a fastening plate 20 bent at right angles outward from the member 18 of the fold which is parallel to the member 19.

To apply this weather strip to the window, 70 the lower sash 7 is formed with a countersink 21 in which the fastening plate 12 of the sash member is countersunk and fastened as by a nail flush with the outside of the sash, so that the offset fold 13 will rest 75 against the outside of the sash.

The fastening plate 17 of the parting strip and stop members 11 is fixed in a recess 22 between the parting strip or stop as the case may be and the corresponding sash, and the 80 angled fastening plate 20 is fastened as by a nail to the outside of the respective sash, the fold 18 of this strip member fitting and sliding within the fold 13 of the sash member.

A recessed molding 23 is also preferably 85 secured to the sash 7 to cover and receive in its recess 24 the complete weatherstrip, and increase the security against the ingress of cold air or egress of the inside warm air.

To permit the removal and replacement of the sashes without detaching this weatherstrip, I make the parting strip 9 and its attached strip member 11, as shown in Figure 4, in separable upper and lower sections, the upper sections of which are preferably fixed in place, and the lower sections of which are removable, the joints 25 and 26 between the upper and lower sections of the interlocking strip members being arcuate and spaced as shown to permit the lower sections to be easily 100

removed laterally after raising the lower sash, both sashes being then lowered for removal after detaching the inner stop 27.

It is evident that the specific details of construction and arrangement herein shown and described may be greatly varied without departing from the boundaries of my invention as defined by the following claims.

It will be seen from the above that the sash

- 10 member 10 is only anchored at one end, leaving the side 15 free to move because of the flexibility of the strip. By this means, if there is any inequality or unevenness in the strip 11, the encompassing loop 10 will expand and contract as the window slides along the loop 11 and will not bind excessively as it would were both ends of the loop 10 anchored in the same way as the ends of the loop 11.
- 15

20 I claim as my invention:

1. A weatherstrip for windows comprising an interlocking strip and stop member having a fastening plate secured between the side of the parting strip of the window and the frame, a fold projecting therefrom, and bearing against the outside of the sash, and a fastening plate bent at a right angle from the fold and fastening to the face of the parting strip, and a sash interlocking member having a fold which is fitted to slide upon the fold secured to the parting strip and having a fastening plate offset from said fold and set into and secured to the outer face of the sash, the interlocking strips formed in sections separable by an arcuate joint at a point near the junction of the sashes when closed.
- 25
2. A weatherstrip for windows comprising a strip and stop member having a fastening plate secured between the side of the parting strip of the window and the frame, a fold or loop projecting therefrom to be engaged by a companion loop, and a fastening plate bent at right angles from the fold and secured to the face of the parting strip, and a sash interlocking member having an embracing loop which is fitted to slide upon the fold secured to the parting strip and having a fastening plate at one end only offset from said fold and set into and secured to the outer face of the sash; the opposite end of this fold or loop being free to expand and contract.
- 30

In testimony whereof I affix my signature.

PASQUALE FRIGIOLA.
